H. W. THAYER

SOUND AMPLIFYING DEVICE

Filed Nov. 17, 1927

UNITED STATES PATENT OFFICE.

HENRY W. THAYER, OF CHATHAM, NEW JERSEY.

SOUND-AMPLIFYING DEVICE.

Application filed November 17, 1927. Serial No. 233,793.

This invention relates, generally to improvements in sound amplifying devices adapted to be magnetically or mechanically actuated to produce amplified sound waves; 5 and the invention has reference, more particularly, to a sound amplifying device of the loud speaker type for use in connection with radio and telephone communication.

This invention has for its principal object 10 to provide a novel construction and arrangement of coupled vibratory diaphragms whereby transmitted sound is reproduced in amplified volume and with a high degree of resonance and clarity throughout the entire 15 range of audio or musical frequencies, and especially whereby improved reproduction and amplified transmission of the lower ranges of audio or musical frequencies is obtained.

With the object of my present invention 20 in view, the same consists in providing a novel construction and arrangement of coaxial diaphragms spaced apart to furnish an intermediate resonance chamber having 25 sound wave outlets, said diaphragms being centrally coupled together for synchronous vibration under the transmitted impulses of a single magnetic or mechanical actuator, such as a telephone receiving unit, a phonograph reproducing unit, or other similar 30 means for transmitting sound wave vibrations.

Other objects of the present invention, not at this time more particularly enumerated, 35 will be clearly understood from the following detailed description of the same.

The invention is clearly illustrated in the accompanying drawings, in which:—

Fig. 1 is a face view of one form of coupled 40 vibratory diaphragms for sound amplification made according to and embodying the principles of this invention, the same being shown in connection with an actuating telephone receiving unit, together with means for mounting the diaphragms in operative 45 relation to the latter; and Fig. 2 is a vertical section, taken on line 2—2 in Fig. 1.

Fig. 3 is a face view in part transverse vertical section of a modified form of coupled 50 vibratory diaphragms for sound amplification which embodies, however, the general principles of construction and arrangement according to this invention; Fig. 4 is a vertical section through the same, taken on line 55 4—4 in Fig. 3.

Similar characters of reference are employed in the above described views, to indicate corresponding parts.

Referring first to Figs. 1 and 2 of the drawings, I have shown therein the preferred 60 form of amplifying device according to this invention, the same comprising a rear diaphragm 5 and a front diaphragm 6 axially aligned together in spaced relation, and respectively mounted on opposite sides of a peripheral frame so as to provide an intermediate resonance chamber 7. In said preferred form, the front diaphragm 6 is of less diameter than the rear diaphragm 5. The peripheral frame for supporting the diaphragms and bounding the resonance chamber 7 comprises an annular frame member 8 disposed to occupy a plane parallel to the planes of the diaphragms; said frame member 8 having at its outer periphery a rearwardly projecting annular shoulder 9 and at its inner periphery a forwardly projecting annular shoulder 10. The marginal portions of the rear diaphragm 5 are registered 70 against and secured to said shoulder 9 and the marginal portions of the front diaphragm are registered against and secured to said shoulder 10, all in such manner that the frame member 8 serves to support the diaphragms for vibration and yet properly spaced apart 75 to provide the desired intermediate resonance chamber 7. Said frame member 8 is provided, in spaced apart relation around its circumference, with a plurality of sound wave outlets or openings 11 leading from the interior of said resonance chamber 7. The diaphragms 5 and 6 may be secured to the frame member 8 by any suitable or convenient 80 means, as, for example, by an adhesive binder, or, if desired, by any form of mechanical fastening. Said diaphragms 5 and 6 may be made of any suitable material which is sufficiently flexible to permit of the required 85 vibratory action thereof; in this connection, I have found parchment, paper, fiber board and similar materials to give very satisfactory results, and to be entirely free from metallic timbre. The diaphragms 5 and 6 are centrally connected together by a substantially rigid intermediate coupling post 12 so 90 that the same vibrate synchronously under the transmitted impulses of a single actuating means, such as a phonographic reproducer, or a magnetic telephone receiver, etc., which operate to transmit vibrations corre- 95 100 105 110

sponding to sound wave vibrations at the frequencies of music and speech.

The present invention is especially adapted to amplify vibrations to reproduce sound in connection with radio communication, and I have therefore illustrated the invention in the form adapting the same to serve as a so-called loud speaker. To such end I provide a suitable supporting standard extending upwardly from a base 13, said standard preferably taking the form of a pair of laterally spaced uprights 14 and 15 having an intermediate transverse shelf or support 16 upon which the telephonic receiving unit is mounted in axial alignment with and behind the diaphragms. Said diaphragms are secured to said uprights 14 and 15 by fastening devices, such as the screws 17, which pass through the frame member 8 into said uprights, the latter preferably having outwardly projecting abutments 18 at the points of connection so that the rear diaphragm 5 is spaced freely from the uprights to avoid any interference with the operative vibration of said diaphragms. Mounted on the shelf or support 16 is a telephonic receiving unit 19 of any well-known type having a transmission rod 20 through which the magnetically induced vibrations of said unit may be transmitted to the amplifying diaphragms. To operatively connect the diaphragms with the transmission rod 20, the rear diaphragm 5 is provided at its exterior face with a centrally located coupling element 21 having a socket portion 22 to receive the free end of said transmission rod 20, which is detachably secured by a set screw 23 or other suitable locking means. Preferably said coupling element is provided with a screw threaded shank 24 which screws into an internally threaded sleeve 25 imbedded in the adjacent end of said coupling post 12, all whereby the vibratory movements of said unit 19 are synchronously transmitted to the diaphragms 5 and 6.

I have found the amplifying device of this invention to be very effective in clearly reproducing, in large volume, sounds such as music and speech without distortion, metallic quality, or necessity for the use of dispersion devices such as horns, etc.; and, furthermore, the device is especially effective in reproducing musical notes, drum beats and the like, in the lower ranges of audio or musical frequencies. In operation, the coupled diaphragms being actuated synchronously, the vibration of the front diaphragm 6 directly excites the free air in contact therewith at its exterior surface to regenerate the sound waves to be communicated, while at the same time, operating in conjunction therewith, the correspondingly vibrating rear diaphragm excites the air within the resonance chamber 7 so that sound waves especially of relatively low frequency range are more efficiently re-

produced and propagated and then dispersed through the outlets or openings 11 of the bounding frame member 8.

In practice, I prefer to employ the form of my invention shown in Figs. 1 and 2, in which the front diaphragm 6 is of less diameter than the rear diaphragm 5, since the comparatively greater surface area of the latter aids in increasing the amplitude of corresponding sound wave producing air pulsations within the resonance chamber 7 to thereby augment the propagation and dispersion of sound waves of relatively low frequency range.

While I prefer to employ the form of my invention shown in Figs. 1 and 2 as aforesaid, I do not wish to be understood as necessarily confining the scope of my invention to such form, for, in its broader aspects, involving a plurality of coupled synchronously vibrated diaphragms with intermediate resonance chamber, it is within its spirit to employ diaphragms of the same size. This latter arrangement I have illustrated in Figs. 3 and 4 of the accompanying drawings, where in the reference character 26 indicates a rear diaphragm and 27 a front diaphragm of substantially equal size. Said diaphragms 26 and 27 are supported in parallel spaced apart relation, so as to provide the desired intermediate resonance chamber 28, by an annular frame member 29 which is interposed and secured between their marginal portions. Said frame member is provided with radial openings 30 spaced around the circumference thereof to provide outlets for the dispersion of sound waves produced by pulsations of air within said resonance chamber. The diaphragms 26 and 27 are centrally connected together for synchronous vibration by the intermediate coupling post 12, in connection with which and said rear diaphragm is provided the coupling element 21 and associated parts already above described, and by means of which the device may be operatively connected with and so as to be actuated by a telephone receiving unit.

I am aware that some changes, other than those already above indicated, may be made in the general construction and arrangement of the sound amplifying device as above described and as illustrated in the accompanying drawings, as well as in the details of the construction of the same without departing from the spirit and scope of the invention as defined by the appended claims. It is therefore to be understood that the specific disclosures of the specification and drawings are to be considered as illustrative and not in a limiting sense.

Having described my invention, I claim:

1. A sound amplifying device, comprising a plurality of spaced diaphragms centrally coupled for synchronous vibration, a peripheral frame means to which the marginal por-

tions of said diaphragms are secured to provide resonance space intermediate the latter, said frame having dispersion openings leading therethrough from said resonance space, and means to transmit vibratory motion to said diaphragms.

2. A sound amplifying device, comprising a pair of axially aligned diaphragms, an annular frame member intermediate the margins of said diaphragms to which the latter are secured whereby a resonance chamber intermediate said diaphragms and bounded by said frame member is provided, said frame member having dispersion openings leading therethrough from said resonance chamber, means to interconnect said diaphragms for synchronous vibration, and means to transmit vibratory motion to said diaphragms.

3. A sound amplifying device, comprising a pair of spaced diaphragms, means connected with the marginal portions of said diaphragms to support the same and to form a resonance chamber therebetween, said latter means having dispersion openings leading therethrough from said resonance chamber, a centrally disposed substantially rigid coupling post interconnecting said diaphragms for synchronous vibration, a telephonic receiving unit, a transmission rod actuated by said unit; external means centrally connected with one of said diaphragms for operatively connecting said transmission therewith, and means to support said diaphragms and unit in assembled cooperative relation.

4. A sound amplifying device, comprising a rear diaphragm, a front diaphragm of reduced diameter, an annular frame interconnecting the margins of said diaphragms to hold the same in spaced relation to provide an intermediate resonance chamber, said frame having dispersion openings leading therethrough from said resonance chamber, a centrally disposed substantially rigid coupling post interconnecting said diaphragms for synchronous vibration, and means to transmit vibratory motion to said diaphragms.

5. A sound amplifying device, comprising a rear diaphragm, a front diaphragm of reduced diameter, an annular frame interconnecting the margins of said diaphragms to hold the same in spaced relation to provide an intermediate resonance chamber, said frame having dispersion openings leading therethrough from said resonance chamber, a centrally disposed substantially rigid coupling post interconnecting said diaphragms for synchronous vibration, a telephonic receiving unit, a transmission rod actuated by said unit, external means centrally connected with said rear diaphragm for operatively connecting said transmission rod therewith, and means to support said diaphragms and unit in assembled cooperative relation.

In testimony, that I claim the invention set forth above I have hereunto set my hand this 12th day of November, 1927.

HENRY W. THAYER.
